UNITED STATES PATENT OFFICE.

ROBERT M. MACGREGOR, OF HARTFORD, CONNECTICUT.

PUNCH PRESS.

1,417,539.

Specification of Letters Patent. Patented May 30, 1922.

Application filed April 30, 1921. Serial No. 465,639.

To all whom it may concern:

Be it known that I, ROBERT M. MACGREGOR, a citizen of the United States, residing at Hartford, in the county of Hartford and 5 State of Connecticut, have invented a new and useful Improvement in Punch Presses, of which the following is a specification.

This invention relates to a machine commonly termed a deep throat punch press. 10 Such machines are more particularly designed for blacksmith shops, structural iron works and other metal working plants which are frequently required to punch, crease or shear metal sheets.

15 The object of the invention is to provide a machine of this nature which is light and portable so that it may be moved up to the work when desired and yet which is strong and powerful and can be operated by any- 20 one to punch, crease or shear relatively thick plates of considerable width and indefinite length. In the accompanying drawings Figure 1 shows a side view of a press which embodies the invention. Fig. 2 is a vertical 25 transverse section of the press on the plane indicated by the dotted line 2—2 on Fig. 1. Fig. 3 is a longitudinal vertical section on the plane indicated by the dotted line 3—3 on Fig. 2 showing the punch operating eccentric.

30 The frame of the machine illustrated comprises two channel bars 1 arranged parallel with each other a slight distance apart and two channel bars 2 arranged parallel with 35 each other a slight distance apart. At their ends the bars are rigidly bolted or otherwise fastened to posts 3 and are supported by legs 4. For the purpose of giving additional strength to the frame and preventing 40 the bars from yielding under the strains of use, downwardly extending brackets 5 are fastened to the under side at the middle of the lower pair of bars and truss rods 6 are passed over these brackets and bolted at 45 their ends to the inside of the lower bars. Upwardly extending brackets 7 are fastened to the top at the middle of the upper pair of bars and truss rods 8 are passed over these brackets and fastened at their ends to the 50 inside of the upper bars. This construction forms a comparatively light yet very rigid frame.

Firmly secured by bolts between the lower bars at the middle is a filling block 9 with 55 a central opening and on the top of this is a die plate 10 having an opening or cavity of

the required shape. Bolted between the upper bars at the middle is a filling block 11 with a central opening. Fitted so that it will move up and down and be guided by 60 the wall of the vertical opening in the block 11 is a ram 12 in the lower end of which a punch or cutter of the required shape is fastened. Supported below the block 11 and pressed downward by springs 14 is a stripping plate 15 of common form.

65 Mounted in bearings in the upper brackets 7 is a shaft 16 on which between the brackets is an eccentric 17. The eccentric strap 18 about this eccentric is connected by a link 19 with the upper end of the ram 12. Fastened on one end of the eccentric shaft is an operating wheel 20 that is provided with handle spokes 21 by means of which the wheel and shaft may be rotated, and spokes 22 bearing 70 weights 23 that are employed to insure a powerful rotatory momentum when the wheel is turned for driving the tool through the metal to be operated upon.

75 This machine is cheap to build. As constructed it is light in weight and can be conveniently moved to the work if desired. With it sheets of relatively thick steel or other metal of considerable width and of any length may be accurately punched, creased, 80 drawn or sheared, according to the conditions and the tools supplied, for the frame is open from end to end and yet is very rigid and great force is exerted through the eccentric driven ram as actuated by the 85 weighted hand wheel.

90 The invention claimed is:

1. A punch press having a frame comprising a pair of parallel bars arranged horizontally and supported at their ends 95 upon legs, a die bed mounted on said bars intermediate the legs, a pair of parallel bars horizontally arranged and supported at their ends above the first mentioned bars, a ram guide mounted on said upper bars in- 100 termediate the end supports, a tool carrying ram movable up and down through said ram guide, rotary means mounted on said upper bars for reciprocating the ram, and a weighted hand wheel for rotating said ram 105 reciprocating means.

2. A punch press having a frame comprising a pair of parallel bars supported upon legs, a pair of parallel bars supported at their ends above the first mentioned bars, 110 brackets projecting down from the middle of the lower pair of bars and projecting up-

2
ward from the middle of the upper pair of bars, truss rods passing over said brackets and having their ends connected with the bars, a die bed fastened between the lower bars at the middle, a ram guide fastened between the upper bars at the middle, a tool carrying ram movable vertically through said ram guide, rotatory means for reciprocating the ram, and a weighted hand wheel 10 for rotating said ram reciprocating means.

3. A punch press having a frame comprising a pair of parallel bars arranged horizontally and supported at their ends upon legs, a die bed mounted on said bars intermediate 15 the legs, a pair of parallel bars horizontally arranged and supported at their ends above the first mentioned bars, a ram guide mounted on said upper bars intermediate the end supports, a tool carrying ram vertically movable through said ram guide, a shaft mounted on said upper bars above the ram guide, an eccentric on said shaft, a connection between the eccentric and the ram, and a weighted hand wheel for rotat- 20
25 ing the shaft.

4. A punch press having a frame comprising a pair of channel bars arranged horizontally and parallel with each other, a pair of channel bars arranged horizontally and parallel with each other above the first mentioned bars, posts connecting the ends of the bar of each pair and the pairs with each other, a die bed mounted on the lower pair of bars, a ram guide mounted on the upper pair of bars, a ram movable in the guide, 30 and rotatory means mounted on said upper pair of bars for reciprocating the ram.

5. A punch press having a frame formed of a pair of horizontally arranged parallel bars and a pair of parallel bars horizontally 40 arranged above the first mentioned bars, said bars being connected at their ends only, and a fixed die, reciprocatory ram and means for reciprocating the ram mounted on said frame intermediate the ends thereof, where- 45 by there is a deep throat on each side of the ram and die and the strains resulting from the action of the tools on the work are sustained on both sides of the ram and die.

ROBERT M. MAC GREGOR.
